SUPPORT

Charles H. Maiben, Logansport, Ind.

Application February 19, 1938, Serial No. 191,562

2 Claims. (Cl. 12—1)

This invention relates to an improved support and is more particularly adapted for use with stapling machines and the like.

As one of its principal objects, the invention seeks to provide a support which will serve effectually to mount a stapling machine and a tape cutting machine for individual selective operation.

Another object of the invention is to provide a support employing means for carrying a tool container or the like between supporting members employed.

Further objects of the invention will appear hereinafter as the description proceeds.

My invention is illustrated in the accompanying drawings wherein:

Figure 1 is a front elevation showing my improved support as it would appear with a stapling machine and a tape cutting machine, portions of 20 said machines being shown in dotted lines.

Figure 2 is a vertical sectional view on the line 2—2 of Figure 1, looking in the direction indicated by the arrows.

Figure 3 is a fragmentary transverse sectional view on the line 3—3 of Figure 2.

Referring now more particularly to the drawings, the numeral 1 indicates in general a pedestal which is formed with an enlarged base portion 2 which and a hollow body portion 3 which is tapered toward its upper end. The pedestal 1 has a hollow interior and is formed, at the junction of the body 3 and base portion 2 with parallel vertical slots 4.

Mounted in the pedestal 1 are treadles 5 and 6 which are of identical construction. As best seen in Figure 2 of the drawings, the treadle 5, which is typical, is provided with a foot engaging portion 7 and a shank 8, the free end of the shank being enlarged and apertured for pivotal reception between the ears of a yoke 9. A trunnion 10 pivotally mounts the treadle 5 in position on the yoke 9. As will be seen, the shank 8 extends through one of the slots 4 and substantially diametrically of the pedestal and through the opposite wall to position between the ears of the yoke 9. Formed on the shank 8 of the treadle 5 is a lug 11 which has swingingly connected thereto a link 12. At best seen in Figure 1 of the drawings, there are mounted on the base portion 2 of the pedestal 1, directly beneath the foot engaging portions 7 of the treadles 5 and 6, stops 13 and 14, the stop 14 being of somewhat greater height than the stop 13. It will be seen that the stop 14 will limit downward movement of the treadle 6 to a relatively short stroke while the

stop 13 will permit the treadle 5 to have a relatively long stroke.

Associated with the pedestal 1 at its upper end is a substantially U-shaped body member 15 which is formed from sheet metal and is relatively wide with respect to the pedestal. The body member 15 is adapted to be held in place on the body 3 of the pedestal 1 by means of a clamping plate 16. The body member 15 forms a part of a supporting frame indicated generally at 17. The supporting frame 17 has an inner U-shaped body member 18 which has upwardly and outwardly directed arms 19 and 20 secured at their outer ends to the upper end portions of the body member 15. The inner body member 18 has a bight portion 21 and arms 22 and 23 which define a compartment 24 for the reception of a tool box or container for tools to be used in making repairs on the machinery carried by the support.

There is mounted on the body member 15 a bracket 25 which has bolts 26 and 27 securing said bracket to said body member near the bight portion thereof. The bracket 25 has legs 28 and 29 which extend rearwardly and receive therethrough the bolts 26 and 27. As will be seen clearly in Figures 2 and 3, the bracket 25 is formed preferably of cast metal or sheet metal of a much heavier gauge than the body member 15. The bracket 25 is adapted to have mounted thereon pairs of spaced stub shafts 30 and 31. The stub shafts 30 and 31 have rotatably mounted thereon pairs of gears 32 and 33. As clearly seen in Figures 1, 2 and 3, the gears are adapted to have trained partially thereabout, an actuating chain 34. The chain 34 has its upper end portion connected with the lower end of a yoke 35 which is connected to a tape cutting machine, shown in dotted lines at 36. The lower end of the chain 34 is pivotally connected to the link 12, which link is, of course, connected with the treadle 5. A chain 37 is partially trained about the gears 33 and has its upper end connected with the actuating mechanism 38 of a stapling machine shown in dotted lines at 39, the lower end of said chain 37 being connected to the treadle 6.

In operation, it will be understood that by depressing the treadles 5 and 6, the tape cutting mechanism 36 and the stapling machine 39 respectively, may be operated. First one may be operated and then the other, or, if occasion requires, both may be operated simultaneously. Attention is directed to the fact that the treadle 5 is mounted for a greater downward stroke than is the treadle 6 for the reason that, with the tape cutting mechanism, a greater downward move-

- ment of the actuating mechanism is required than is required when using the stapling machine without the tape cutting machine or mechanism thereon. It should be understood that the stops 5 **13** and **14** may be removed or substituted one for the other when it is desired to vary the distance of the stroke of either of the treadles. It should also be understood that any type of machine 10 operable by a treadle may be mounted on the support and I do not desire to limit myself to stapling mechanism in this respect, although it has been found that my support is particularly adapted for use in connection with such mechanism.
- 15 In view of the fact that the compartment **24** is defined between corresponding legs of the inner and outer members **21** and **15** respectively, a tool kit may be placed for use with the utmost convenience should repairs to the mechanism be 20 necessary. It is thought that further description of my improved support will not be necessary.
- Having thus described the invention, what I claim is:
1. A device of the class described including a 25 pedestal, an outer member carried by the pedestal, an inner member carried by the outer member and having legs connected with said outer member, said legs being oppositely presented and

adapted to support mechanism, treadles carried by the pedestal, a bracket carried by the outer member, stub shafts carried by the bracket, pairs of gears carried by the stub shafts, and chains trained about the gears of each pair of gears and being adapted to extend into the pedestal, said chains having corresponding end portions connected with the treadles and having corresponding end portions adapted to be connected to actuating mechanisms of the mechanism carried by the legs, said chains being adapted to be shifted at movement of the treadles for shifting said actuating mechanisms.

2. In a support, a pedestal having a base portion and a hollow body portion, treadles pivotally mounted in the pedestal, an outer member associated with the pedestal, means connecting the outer member with the pedestal, an inner member connected with the outer member and having legs defining an open compartment between the legs, said legs mounting an open mechanism to be carried on the support, and means operatively connecting the treadles with the mechanism on the support, said means being shiftable at depression of the treadles for shifting said operating mechanism, said compartment being adapted to receive a tool kit.

CHARLES H. MAIBEN.
